US00D700609S

(12) **United States Design Patent**
Sugitani et al.

(10) **Patent No.:** **US D700,609 S**
(45) **Date of Patent:** **** Mar. 4, 2014**

(54) **SCANNER**

(75) Inventors: **Minoru Sugitani**, Kahoku (JP); **Satoshi Kuroda**, Kahoku (JP); **Masaaki Yamashita**, Kahoku (JP)

(73) Assignee: **PFU Limited**, Kahoku-shi, Ishikawa (JP)

(**) Term: **14 Years**

(21) Appl. No.: **29/426,076**

(22) Filed: **Jun. 29, 2012**

Related U.S. Application Data

(63) Continuation of application No. 29/404,709, filed on Oct. 25, 2011, now Pat. No. Des. 673,155.

(30) **Foreign Application Priority Data**

Jun. 16, 2011 (JP) 2011-13631

(51) LOC (10) Cl. **14-02**

(52) U.S. Cl.

USPC **D14/423; D14/453**

(58) **Field of Classification Search**

USPC ..... D14/420-425; D16/232, 229, 235, 221, D16/135; D18/36; 353/115, 119, 122, 353/DIG. 3, DIG. 4; 396/155, 133, 86; 358/474-498; 348/370, 373, 376, 374, 348/375; 248/187.1, 593, 276.1, 281.11; D26/63, 65, 64, 62, 135, 61, 107, 109, D26/51; D32/22-33

See application file for complete search history.

CLAIM

The ornamental design for a scanner, as shown and described.

DESCRIPTION

FIG. 1 is a front perspective view of a scanner showing our new design;

FIG. 2 is a front view thereof;

FIG. 3 is a left side view thereof;

FIG. 4 is a top plan view thereof;

FIG. 5 is a bottom plan view thereof;

FIG. 6 is an enlarged fragmentary perspective view of FIG. 1; and,

FIG. 7 is an enlarged fragmentary front view of FIG. 2.

Any material in the priority application which is not present herein forms no part of the claimed design.

Broken lines and unshaded portions contained within broken lines are not claimed.

1 Claim, 3 Drawing Sheets
